UNITED STATES PATENT OFFICE.

PORT A. PRICE, OF RICHMOND, CALIFORNIA.

DIRT LOADER.

Application filed January 7, 1924. Serial No. 684,813.

To all whom it may concern:

Be it known that I, PORT A. PRICE, a citizen of the United States, residing at Richmond, in the county of Contra Costa, 5 State of California, have invented certain new and useful Improvements in Dirt Loaders; and I do hereby declare the following to be a full, clear, and exact description of the invention, such as will enable 10 others skilled in the art to which it appertains to make and use the same.

This invention relates to new and useful improvements in scrapers and elevators, and particularly to devices for scraping and elevating dirt, in streets, roads, and the like 15 places.

One object of the invention is to provide a device of this character wherein the amount of dirt scooped up is delivered to the 20 conveyor in a constant stream of uniform dimensions.

Another object is to provide a device of this character wherein the dirt is delivered to the elevator buckets when said buckets 25 are in inclined position, thereby obviating loss of spilling of the dirt experienced in the ordinary devices of this class where the buckets dig into the mass of dirt being lifted by the digging blade or shovel.

30 Other objects and advantages will be apparent from the following description when taken in connection with the accompanying drawings.

In the drawings:

35 Figure 1 is a side elevation of a machine of this type, made in accordance with the present invention.

Figure 2 is a top plan view of the same.

Figure 3 is an enlarged vertical longitudinal central sectional view on the line 40 3—3 of Figure 2.

Referring particularly to the accompanying drawings, there is shown a frame which includes the longitudinal side bars 10 and 45 the transverse connecting and spacing bars 11. At a suitable distance from the rear end, the side bars are offset outwardly, as at 12, and thence extended rearwardly in parallel relation, as shown at 13. Between 50 these portions 13, and against the offset portions 12, there is disposed the dirt receiving box 14, said box having its upper side open, and being provided with a door 15 in the lower portion of its rear wall. In the upper 55 portion of the front wall of the box there is formed a recess 16, to which reference will

be made later herein. The box is properly secured to the bars 10, as by means of the rivets 17. Extending from the upper portion of the front wall of the box, to the intermediate portions of the side bars 10, is a brace arm 18. Extending from the sides of the box, and connected thereto, and to the rear ends of the bars 10, are the brace arms 19. Properly supported in the rear ends of the bars 10, beneath the box, is a transverse axle or shaft 20, on which is supported a roller 21, the bottom of the box being formed on a line which curved in conformity to the upper portion of the roller.

Secured to the front wall of the box, and arranged at opposite sides of the recess 16, are the bearing brackets 22, which support the transverse shaft 23. Disposed longitudinally of the machine, and in an upwardly and rearwardly inclined position, is the frame 24 of an elevator, said frame extending through the recess 16, and receiving therethrough the said shaft 23, whereby said frame is mounted or suspended for pivotal movement. The forward, or lower end of the frame of the conveyor or elevator, is disposed between the side bars 10, in close relation to the surface of the ground. Mounted for rocking movement on the forward end of the main frame, is a rock shaft 24', the intermediate portion of which is formed with a crank 25, and pivotally connected to this crank is a depending link 26, which has its lower end connected with the frame of the elevator. On the shaft 24' there is fixed an operating lever 27, by means of which the shaft may be rocked to raise and lower elevator frame.

The lower ends of the side boards of the elevator frame are formed with the upwardly and forwardly extending enlargements 28, and disposed through the extremities of said enlargements is a transverse shaft 29 which supports a ground engaging 95 roller 30. Secured to the elevator frame, beneath the lower end, and spaced in concentric relation to the lower rear portion of the roller 30, is a digging blade or shovel 31.

Rotatably supported in the ends of the 100 elevator frame, at the upper and lower ends, respectively, are the transverse shafts 33 and 34, and mounted on the end portions of the shafts, inwardly of the sides of the elevator frame, are the sprocket wheels 35. Engaged around these sprocket wheels are 105 the conveyor chains 36, and secured to the

chains and extending transversely therebetween, are the conveyor buckets 37. It will be noted that these buckets flare toward their forward portions, and include a back vertical wall, a bottom, and the approximately triangular end walls. Carried by the upper portions of the side walls of the box, are the upwardly extending brackets 38, and rotatably supported in these brackets is a transverse shaft 39, carrying on one end a sprocket wheel 40. On the corresponding end of the rear ground roller 21 there is secured a large sprocket wheel 41, and engaged around the sprockets 40 and 41 is a drive chain 42. On the adjacent end of the upper shaft 33, of the conveyor is a sprocket wheel 43, of a diameter approximately equal to that of the wheel 40, and engaged with this wheel 43 is the lower or forward lap of the drive chain 42, and whereby motion is transmitted to the elevator chains 36. On the upper shaft 33, between the sprockets 35 and 43, there is located a clutch means 44, the same being operable by means of a lever 45, mounted on the side of the elevator frame of the machine, and connected to said lever by the link 46. A seat 47 is mounted on the front portion of the main frame, for the driver, while the extreme front end of the frame is supported on the wheeled truck 48.

It will be noted that the curved portion of the blade 31 extends upwardly so that the dirt which is driven thereon will fall onto the buckets of the conveyor at the time when the buckets are in their inclined position, and moving upwardly on the upper side of the chain. Thus the buckets are not required to dig their way through, and tend

to press back the dirt as it is delivered by the shovel.

The roller 30, being spaced the required distance above the shovel, will ride on the dirt ahead of the shovel, and thereby regulate the depth into the dirt which the shovel will penetrate. The roller also serves to pack the dirt so that it is delivered in a uniform stream, to the conveyor buckets. At opposite sides of the frame 24 are the lateral wings 49 which prevents spilling of dirt.

Mounted on, and extending transversely between the side boards of the elevator frame, and at the lower ends thereof, is a scraper blade 50, the free edge of which engages the peripheral face of the roller 30, to remove the soil therefrom, and maintain the same in a clean condition, and thereby prevent change of the space between the roller and the shovel.

What is claimed is:

A dirt elevating device including an endless inclined conveyor, a curved digging element mounted in advance of the lower end of the conveyor and adjacent thereto, guiding means between the digging element and the end of the conveyor for guiding the dirt onto the conveyor, and a packing roller mounted above the digging element and having its periphery concentric with the upper face thereof for packing the dirt immediately prior to its passage to the conveyor.

In testimony whereof, I affix my signature, in the presence of two witnesses.

POR T A. PRICE.

Witnesses:

Mrs. IDA BETTS,
HUGH DOUGHERTY.
